Primary Examiner — Cathron Brooks*Assistant Examiner* — Kevin Rudzinski(74) *Attorney, Agent, or Firm* — Stewart & Irwin, P.C.;
Dennis S. Schell(57) **CLAIM**

The ornamental design for a LED flood light, as shown and described.

DESCRIPTION

FIG. 1 is a front perspective view of the new design;

FIG. 2 is a front view thereof;

FIG. 3 is a left side view thereof;

FIG. 4 is a right side view thereof;

FIG. 5 is a rear view thereof;

FIG. 6 is a top view thereof;

FIG. 7 is a bottom view thereof; and,

FIG. 8 is a rear perspective view thereof.

The broken lines shown in the drawings are for the purpose of illustrating aspects that form no part of the claimed design.
